UNITED STATES PATENT OFFICE.

MARTIN DE LIN, OF HOLLAND, MICHIGAN.

DIE.

Application filed June 30, 1924. Serial No. 723,085.

To all whom it may concern:

Be it known that I, MARTIN DE LIN, a citizen of the United States of America, residing at Holland, in the county of Ottawa and State of Michigan, have invented certain new and useful Improvements in Dies; and I do hereby declare the following to be a full, clear, and exact description of the invention, such as will enable others skilled in the art to which it appertains to make and use the same.

This invention relates to dies for folding the sides and ends and joining the corners of sheet metal boxes by a single operation. 15 The die embodying this invention is adapted to receive a flat sheet metal blank and, by a single thrust of the plunger of the punch press machine in which the die is operated, to fold the sides and ends of the blank at right angles to the bottom and to fold the corner flaps about each other and press the seam down and deliver the completed box.

Heretofore several dies and several operations have been necessary to produce the same result and the die of this invention is a very valuable addition to the art as, by its use, a very great increase of production and decrease of labor and machinery cost is effected.

30 The construction and operation of the die will be more clearly understood from the following description and the invention is specifically pointed out in the claims, reference being had of the accompanying drawing in which,

Fig. 1 is a plan view of the sheet metal blank used to form a box.

Fig. 2 is a perspective view of a box formed from the blank by a single operation 40 of the die.

Fig. 3 is an enlarged fragmentary perspective of one corner of the box showing how the flaps are folded over each other and pressed against the ends of the box to join the corners.

Fig. 4 is an enlarged fragmentary sectional elevation showing the comparatively sharp corners of the sides of the die over which the sides of the box are drawn to fold them vertically.

Fig. 5 is an enlarged fragmentary sectional elevation showing the rounded corners of the ends of the die over which the ends of the box are drawn to fold them vertically.

55 Fig. 6 is a plan view of the die with the

blank laid thereon, with a part of the blank broken away.

Fig. 7 is a vertical sectional elevation on the line 7—7 of Fig. 6 showing the blank at the beginning of the forming operation. 60

Figs. 8 to 12 inclusive are enlarged fragmentary sectional views showing different parts of the die and one corner of the box being operated upon at successive stages of the operation. 65

Fig. 13 is an enlarged fragmentary perspective of one corner of the die with one of the forming rollers removed and,

Fig. 14 is an enlarged fragmentary perspective of one corner of the box in partially 70 formed condition.

Like reference numbers refer to like parts in all of the figures.

The box to be formed by this die comprises a bottom 1, vertical sides 2, and vertical ends 75 3. The drawings show the structure in which the longer members are termed sides and the shorter members ends, these terms being used as a means of distinguishing one from the other and not in any way attempting to limit the shape of the box to that shown, as the box might be square or the relative proportion of the so called ends and sides reversed or altered. 80

The vertical edges of the sides 2 are each 85 provided with integrally formed flaps 4 and the vertical edges of the ends 3 are provided with integrally formed flaps 5, the flaps 4 being considerably wider than the flaps 5. The blank illustrated in Fig. 1 is stamped 90 from a piece of sheet metal preparatory to forming the box in the die.

The die comprises the side members 6 and the end members 7 joined together in the form of a rectangle with rectangular opening 95 through them open at both the top and bottom, the said opening being of the exact size as the outside dimensions of the box. Five sets of forming rollers are set into recesses in the inner face of the end members 7 of 100 the die at the respective corners, each set comprising four rollers and one roller of each set being located at each respective corner of the die in superimposed relation. The rollers are so arranged that they will 105 act successively upon the corner flaps 4 and 5 of the box as the blank is forced through the die from top to bottom as hereafter more fully described.

Upon the top sides of the die the guide 110

blocks 8 are fastened by means of which the blank is properly located upon the die. A plunger 9, rectangular in shape and of the exact size as the interior of the box is provided to force the blank through the die. It is customary to use this die in connection with a punch press machine in which case the plunger 9 is attached by suitable means to the vertically reciprocating member of the punch press by which it is moved up and down but it is possible to actuate the plunger manually or by any other suitable means.

As the plunger descends upon the blank and forces it into the opening of the die the first action is to fold the sides 2 and ends 3 upwardly at right angles with the bottom as they are drawn over the upper corners of the side members 6 and end members 7 of the die. It will be noted that the upper corners of the side member 6 are relatively sharp being rounded only sufficiently to remove the sharp corner which would have a tendency to cut the metal of the blank, while the upper corners of the end members 7 are considerably rounded. The result of this construction is that the sides 2 are folded upward in advance of the ends 3 as illustrated in Figs. 4 and 5 so that the flaps 4 formed integrally with the sides 2 first reach the vertical position and as the ends 3 and the flaps 5 thereon rise the said flaps 5 engage the flaps 4 and are turned outward from the end of the box against the inner surfaces of the flaps 4 as shown in Fig. 14.

The upper set of forming rollers 10 have a radius equal to the radius of the upper corner of the end 7 and their ends are spaced away from the side members 6 and 11 a distance equal to the combined thickness of the flaps 4 and 5 and as the plunger 9 forces the blank through the die the flaps 4 and 5 enter the spaces 11 and the rollers 10 form a sharp bend at the juncture of the flaps 5 with the ends 3. To permit the flaps 4 and 5 to form themselves to approximate shape before being engaged by the rollers 10 and to allow easy entrance into the spaces at the ends of said rollers the notches 12 are cut into the sides 6 of the die opposite the ends of the rollers 10.

After the flaps leave the rollers 10 which have sharply bent the flaps 5 against the inner surfaces of the flaps 4 and left the edges of the flaps 4 projecting beyond the flaps 5 they are engaged by the second set of forming rollers 13, each of which has an annular groove which curls the projecting edge of the flaps 4 over the flaps 5. Further downward movement of the plunger causes the flaps to be engaged by the third set of forming rollers 14, the axes of which are arranged at right angles to those of the other rollers and longitudinally of the die.

The rollers 14 press the flaps against the sides 6 of the die and fold the flap 4 tightly over the flap 5. The next operation by the fourth set of rollers 15, each of which is grooved annularly, partially folds both of the flaps 4 and 5 which have previously been folded over each other, against the ends of the box and the final set of rollers 16 press the flaps against the ends of the box and flattens the seam. 75

During all of the above described operations the plunger 9 has held the sides and ends in true shape against the inner surfaces of the die and its movement or stroke is long enough to force the box clear of the die through its open bottom where the box is removed from the plunger and the plunger returns to its starting position. 80

The movement of the plunger in forcing the blank through the die to form the box, is comparatively fast and the forming operations occur very rapidly. The guide blocks 8 allow the blanks to be located upon the die with little lost time between strokes of the plunger and a very large quantity of boxes may be completed with the die in a short time. Furthermore the boxes so formed are of uniform size and accurate shape. 90

I claim:

1. A device of the class described comprising a die having a rectangular opening therethrough, rollers mounted at the corners of the die adapted to successively operate upon the flaps of the sides and ends of a box blank to interlock them as the blank from which the box is formed is forced through the die, and means for forcing a blank through the die substantially as described. 100

2. A device of the class described comprising a die having a rectangular opening therethrough, the upper corners of the sides of the die being relatively sharp and the upper corners of the ends of the die being relatively rounded, means within the die at each corner for folding one of the corner flaps over the other and for folding the flaps against the ends of the box as the blank is forced through the die, and means for forcing a blank through the die. 110

3. A device of the class described comprising a die having an opening therethrough of the same size as the outside of a box to be formed, a plurality of rollers located in superimposed relation at each of the respective corners of the die to successively operate upon the respective side and end flaps of the blank from which the box is to be formed to fold them about each other and a plunger of the same size as the inside of the box to force the blank through the die. 120

4. A device of the class described comprising a die having a rectangular opening 125

therethrough, a plurality of sets of rollers mounted at the respective corners of the die in superimposed relation and adapted to successively operate upon the corner flaps of a blank from which a box is to be formed to fold one flap over the other and to fold both flaps against the end of the box, and means for forcing the blank through the die.

5. A device of the class described comprising a die having a rectangular opening therethrough, the upper corners of the sides of the die being relatively sharp and the upper corners of the ends of the die being relatively rounded, a plurality of forming 10 rollers arranged in superimposed relation at each respective corner of the die to operate successively upon the corner flaps of the box, the rollers at each respective corner being adapted to fold one of the flaps over 15 the other and to fold both of the flaps against the end of the box, and means for forcing a blank through the die.

6. A device of the class described comprising a die having side members and end 20 members joined together in rectangular relation with a rectangular opening there- 25

through, the upper corners of the side members being relatively sharp and the upper corners of the end members being relatively rounded, a set of rollers arranged near the top of the die, one at each corner thereof and spaced away from the sides of the die a distance equal to the combined thickness of a side flap and an end flap of the box, a second set of rollers located beneath the first set, 30 one at each corner of the die, each having an annular groove to curl one flap over the other, a third set of rollers located beneath the second set, each being adapted to complete the folding operation of one flap over 35 the other, a fourth set of rollers located beneath the third set, each having an annular groove to partially fold both flaps against the end of the box, a fifth set of rollers located beneath the fourth set and adapted to 40 complete the folding of both flaps against the end of the box, and a plunger the same size as the inside of the box, adapted to force 45 a blank through the die.

In testimony whereof I affix my signature.

MARTIN DE LIN.
